US00D703313S

(12) **United States Design Patent**
Ng et al.

(10) **Patent No.:** US D703,313 S
(45) **Date of Patent:** ** Apr. 22, 2014

(54) **ADJUSTABLE FOREHEAD SUPPORT DIAL FOR RESPIRATORY MASK**

(71) Applicant: **ResMed Limited**, Bella Vista (AU)

(72) Inventors: **Eva Ng**, Erskineville (AU); **Vincent Chu**, Shatin (HK); **Mark Bertinetti**, Ermington (AU); **Scott Alexander Howard**, Frenchs Forest (AU); **Murray William Lee**, Quakers Hill (AU); **Philip Thomas Stallard**, Denistone East (AU); **Joshua Adam Gudiksen**, Mortdale (AU); **Susan Robyn Lynch**, Bella Vista (AU)

(73) Assignee: **ResMed Limited**, Bella Vista (AU)

(**) Term: **14 Years**

(21) Appl. No.: **29/465,033**

(22) Filed: **Aug. 23, 2013**

Related U.S. Application Data

(63) Continuation of application No. 29/444,187, filed on Jan. 28, 2013, now Pat. No. Des. 691,714, which is a continuation of application No. 29/347,600, filed on Mar. 11, 2010, now Pat. No. Des. 677,778, which is a continuation of application No. 29/311,764, filed on Jun. 15, 2009, now Pat. No. Des. 613,853, which is a continuation of application No. 29/268,827, filed on Nov. 14, 2006, now Pat. No. Des. 596,739.

(57) **CLAIM**

The ornamental design for an adjustable forehead support dial for respiratory mask, as shown and described.

DESCRIPTION

FIG. 1 is a front perspective view of an adjustable forehead support dial for respiratory mask showing our new design; FIG. 2 is a reverse perspective view thereof;

FIG. 3 is a front view thereof;

FIG. 4 is a rear view thereof;

FIG. 5 is a top view thereof; and,

FIG. 6 is a left side view thereof.

The broken lines represent environment or structure of the adjustable forehead support dial for respiratory mask and do not form part of the claimed design.

1 Claim, 3 Drawing Sheets
